COMBINED WATERPROOF HOUSING AND CAMERA

Jordan Klein, Miami, Fla.

Application November 2, 1955, Serial No. 38,697

Term of patent 14 years

(Cl. D61—1)

FIG. 1

FIG. 4

FIG. 5

Fig. 1 is a front elevational view of a combined waterproof housing and camera, showing my new design;

Fig. 2 is a top plan view thereof;

Fig. 3 is a rear elevational view thereof;

Fig. 4 is a side elevational view thereof, looking from the left of Fig. 1; and

Fig. 5 is a side elevational view thereof, looking from the right of Fig. 1.

I claim:

The ornamental design for a combined waterproof housing and camera, as shown.
